US0D1103770S

(12) **United States Design Patent** (10) Patent No.: **US D1,103,770 S**
(45) Date of Patent: ** Dec. 2, 2025

(54) **PORTABLE BOTTLE**

(71) Applicant: **Soo Wan Hong**, Hadong-gun (KR)

(72) Inventor: **Soo Wan Hong**, Hadong-gun (KR)

(**) Term: **15 Years**

(21) Appl. No.: **35/522,237**

(22) Filed: **Feb. 28, 2024**

(80) **Hague Agreement Data**

Int. Filing Date: **Feb. 28, 2024**

Int. Reg. No.: **DM/239602**

Int. Reg. Date: **Feb. 28, 2024**

Int. Reg. Pub. Date: **Sep. 6, 2024**

(30) **Foreign Application Priority Data**

Sep. 4, 2023 (KR) 30-2023-0034482
